UNITED STATES PATENT OFFICE

159,191

GLASS SALAD BOWL OR SIMILAR ARTICLE

Albert J. Dreitzer, New York, N. Y., assignor to Pitman-Dreitzer & Co., Inc., New York, N. Y., a corporation of New York

Application October 28, 1949, Serial No. 5,758

Term of patent 14 years

(CL. D36—2)

To all whom it may concern:

Be it known that I, Albert J. Dreitzer, a citizen of the United States of America and a resident of New York, in the county of New York and State of New York, have invented a new, original, and ornamental Design for a Glass Salad Bowl or Similar Article, of which the following is the specification, reference being had to the accompanying drawing, forming a part hereof:

I claim:

The ornamental design for a glass salad bowl or similar article, substantially as shown.

ALBERT J. DREITZER.
